UNITED STATES PATENT OFFICE

JOSEPH J. KNAPE, OF GRAND RAPIDS, MICHIGAN, ASSIGNOR TO KNAPE & VOGT MANUFACTURING COMPANY, OF GRAND RAPIDS, MICHIGAN, A CORPORATION OF MICHIGAN

BRACKET

Application filed September 3, 1929. Serial No. 390,129.

This invention relates to an adjustable bracket which is of utility in many places for holding and supporting horizontal shelves usually in show cases or other store furnishing enclosures, though not in any sense restricted in use to either show case or store furnishing use.

The present invention is concerned with various improvements in the construction of bracket shown in United States Patent No. 941,682, issued November 30, 1909 and has for its primary object and purpose the application of various improvements to the bracket shown in said patent, whereby it is more stable in its connection to its support and is less liable to become disconnected therefrom should the attaching or clamping bolt used be not tightened as fully as it should be, or if it becomes loosened after it has been once tightened.

The invention which I have made is fully described in the following description, taken in connection with the accompanying drawing, in which,

Fig. 1 is a perspective view of the improved adjustable bracket of my invention attached to a support.

Fig. 2 is a fragmentary side elevation with parts broken away and shown in section, showing the bracket attached to a support.

Fig. 3 is a fragmentary side elevation of the bracket.

Fig. 4 is an elevation and section substantially on the plane of line 4—4 of Fig. 2, looking in the direction indicated by the arrows.

Fig. 5 is a vertical section of the bracket on the plane of line 5—5 of Fig. 3, and,

Fig. 6 is a fragmentary horizontal section substantially on the plane of line 6—6 of Fig. 3, looking downward as indicated.

Like reference characters refer to like parts in the different figures of the drawing.

The adjustable bracket of my invention is adapted to be supported on a vertically positioned channel which preferably has a web 1 and rearwardly turned flanges 2 and 3. The bracket is to be located at the front side of the web. A plurality of vertical and equally spaced apart key-hole slots are cut through the web, each having an upper enlarged sub-

stantially circular portion 4 and a lower narrowed portion 5, as shown.

In the construction of the bracket, a bracket arm 6 is used made of flat metal, the outer free end of which may be equipped with an upwardly extending self-retaining lip 7. At its rear end said arm is considerably widened vertically and it has an opening 8 therethrough near its rear end with an opening of less width extending from the rear side of the opening 8 to the rear edge of said arm. The arm 6 at said rear vertical edge is also provided with a rearward projection 9 which extends back of the rear edge of the arm a distance equal substantially to the thickness of the web 1 of the channel. Its height in the form shown is somewhat over one-half of the distance between the upper and lower end of a key-hole slot described.

At each side of the rear end of the bracket arm 6 a metal plate 10 is located and permanently secured by rivets which pass through both plates and the arm 6. Each of said plates at both its upper and lower ends and at its rear edge is formed with outwardly turned lips 11 which are located at right angles to the body of the plate, and the rear sides of all of said lips 11 lie in the same vertical plane with the rear edge of the arm 6 and the rear edges of said plates 10. Said plates 10 at their inner edges are also formed with downwardly and rearwardly extending fingers 12, which are located one at each side of the projection 9, said projection 9, however, at its upper part extending a short distance above the upper portions of said ears. Each of the side plates 10 described, opposite the opening in the bracket arm extending from the opening 8 therein to the rear edge thereof, is outwardly embossed or pressed, as indicated at 13.

A bolt 14, having a head 15, passes through the opening or passage made by said embossings 13 and into the opening 8 of the bracket arm being there equipped with a clamping nut 16, as shown. The shank 90 of the bolt is substantially square in cross section so that it is held from turning movement.

When a bracket of this character is attached to the vertical channel support the hooks 12 are first passed into one of the 100

key-hole slots in the web 1, and the head 15 of the bolt entered into the enlarged upper portion 4 of the key-hole slot next above, and then the entire bracket moved downward 5 so that the shank of the bolt is received in the lower portion 5 of the upper slot and the hooks 12 in the lower portion 5 of the lower slot. At the same time the projection 9 extends into the same key-hole slot as that in 10 which the hooks are located.

By tightening the clamping nut 16 the bracket is brought securely against the front side of the web 1 and the rear sides of the lips 11 similarly clamped against the web.

15 The bracket is held against any tendency to lateral swinging movement by the lips 11 even though the nut 16 should be thereafter loosened or if it is not properly tightened in the first instance. Also by reason of the 20 projection 9 extending into the lower key-hole slot, a loosening of the nut 16 will not permit disengagement of the bracket from its support in an upward direction, but the nut will have to be threaded back on the bolt 25 for a considerable distance before the bracket can be elevated and at the same time pulled outwardly far enough to allow the upper end of the projection 9 to pass by the upper side of the key-hole slot in which it is located.

30 Of course, by loosening the nut 16 and running it out on the bolt a sufficient distance, the bracket can be readily detached and adjusted to a different position on the channel support making use of other key-hole 35 slots in the new attachment.

The invention is defined in the appended claims and is to be considered comprehensive of all forms of structure coming within their scope.

40 I claim:

1. A bracket comprising, a bracket arm of flat metal adapted to be positioned in a vertical plane, a projection extending from an end of said arm and located between the upper 45 and lower edges of the arm, vertical plates secured one at each side of the arm at said end thereof and having their outer edges flush with the said end of the arm whereby said projection extends beyond the adjacent 50 edges of said plates, and hook members extending from the edges of said plates downwardly and beyond said end of the arm, said hook members being located below the upper end of said projection.

55 2. In combination, a vertical support having a plurality of vertically spaced apart keyholes therein, a bracket arm having an opening near the upper corner thereof, a bolt extending into said opening and projecting 60 from the arm and of a shape to engage the sides of the lower portion of a slot, a hook near the lower part of the arm to engage the next lower slot in the support, and a projection on said arm extending above the hook 65 and away from the adjacent end of the arm.

a distance equal substantially to the thickness of the support in which the slots are cut, said projection extending into the same opening with the hook.

In testimony whereof I affix my signature.

JOSEPH J. KNAPE.
